UNITED STATES PATENT OFFICE

147,843

DESIGN FOR A TOOTHBRUSH HOLDER

Robert C. Fedanzo and Andrew S. Gagliardo,
Chicago, Ill.

Application February 2, 1946, Serial No. 126,188

Term of patent 7 years

(Cl. D4—3)

To all whom it may concern:

Be it known that we, Robert C. Fedanzo and Andrew S. Gagliardo, citizens of the United States and residents of Chicago, in the county of Cook and State of Illinois, have invented a new, original, and ornamental Design for a Toothbrush Holder, of which the following is a specification, reference being had to the accompanying drawing, forming a part thereof.

We claim:

The ornamental design for a toothbrush holder, as shown.

ROBERT C. FEDANZO.
ANDREW S. GAGLIARDO.
